Joseph Pratt of Boston Mass.

Afignor to

Dowert. Pratt & Co of Boston aforesaid

Letter Patent No 527 Dated Nov 16th 1852

mmmmmm

The schedule referred to in these Letter Patent, and making part of the same

mmmmmm

To all Persons to whom these Presents shall come,

Be it known that I Joseph Pratt

of Boston in the County of Suffolk and State of Massachusetts, have produced a new and ornamental design for a parlor grate or open fireplace and I do hereby declare that the same is represented in the accompanying drawings of which Figure 1. denotes a top view of the said fireplace Figure 2. a front elevation of it. Figure 3 a central, vertical and transverse section of it taken on a line from A to B of Figure 1. Figure 4 is a horizontal section taken on a line from C to D of Figure 2.

The main hearth plate is seen at E while the fender hearth is represented at F the edges of each being made with mouldings and ornaments.

2
as seen in the drawings.

Their upper surfaces are indented with rayed channels. Resting on the main hearth plate and on opposite sides of the fender, are two rectangular panelled pedestals whose panels are each ornamented with an egg and two lance points in alto relief.

Above each of the said bases and resting on them is an ovolo surmounted by a fillet, on which reposes a sculptured pilaster. The two pilasters support on their imposts a semi-circular arch which is sprung from one to the other, and is ornamented throughout by a fasciae in relief, which at its upper part is overlaid by a double scroll or rams head modillion. The sides of the arch rest against projecting and grooved panels whose external boundaries are terminated by voluted pilasters, which rest respectively on the above mentioned panelled bases.

Above these voluted pilasters, and the arch is an entablature mantel which has its upper surface panelled into two sealed panels, that spring laterally in opposite directions from a circular rope in bass relief. The external boundary of the mantel, consists of an inverted cyma recta reposing on a fillet and surmounted by a fillet. Leaf and vine work ornaments are made in bass relief, on the external surface of the inverted cyma. There is a circular cavetto enclosed within the circular rope, which cavetto is ornamented with leaf work and sustains or is surmounted by an ornamented cap plate.

The blower is seen at C, it being panelled ornamented and shaped as seen in the drawings. It reposes on the grate H which forms part of my design.

The remaining particulars of the design are fully represented in the drawings, and will be readily comprehended by persons skilled in the arts of designing and carving or sculpturing such articles. The word "Patented" and the figures 1.8.52. as seen in relief in Figure 2 and under the entablature or mantel forms no part of my design.

I claim as new and of my production the design & configuration of the ornaments of the front plate and mantel or top plate of the fire place, the hearth, the fender plate and the blower as represented in the drawings and as above described the whole forming an ornamental design for a parlor plate.

In testimony whereof I have hereunto set my signature this tenth day of

Des. 3
September A.D. 1852.
